UNITED STATES PATENT OFFICE.

WILLIAM G. KENDALL, OF NEWARK, NEW JERSEY.

VANITY CASE.

Application filed August 16, 1922. Serial No. 582,204.

To all whom it may concern:

Be it known that I, WILLIAM G. KENDALL, a citizen of the United States, and a resident of Newark, in the county of Essex and State of New Jersey, have invented a new and Improved Vanity Case, of which the following is a full, clear, and exact description.

The present invention relates to new and useful improvements in vanity cases and it pertains more particularly to a new and novel method of retaining a powder compact in operative position within the vanity case.

It is one of the objects of the invention to construct a new and novel means for retaining a powder compact within a vanity case.

It is a further object of the invention to so construct the retaining means that the powder compact carrier may be removed from the vanity case at will.

With the above and other objects in view, reference is had to the accompanying drawings, in which—

Figure 1 is a top plan view of a vanity case constructed in accordance with the present invention;

Fig. 2 is a transverse sectional view taken on the line 2—2 of Fig. 1.

Referring more particularly to the drawings, the reference character 11 designates the vanity case, 12 designates the cover thereof, and 13 designates the hinge by means of which the cover is secured to the vanity case. The vanity case has an open side 14, and adjacent said open side the side walls of the vanity case are pressed inwardly to provide an inwardly disposed annular shoulder 15.

The reference character 16 designates a powder compact and said powder compact is mounted in a metallic carrier 17 which is adapted to be received within the vanity case 11 as clearly shown in Fig. 2. The reference character 18 designates the inwardly-disposed side flanges of the compact carrier 17, which provide an intervening V-shaped space between the side walls of the vanity case and the side edges of the compact carrier 17. The reference character 19 designates a resilient metal band adapted to be positioned in the vanity case in such a manner that its upper edge engages beneath the

inwardly disposed shoulder 10 as designated by the reference character 21. The lower edge of this metallic band 19 is provided with a plurality of resilient tongues 22, said tongues being formed by slitting the band upwardly from the bottom edge as designated by the reference character 23. Each end of this band is provided with a lug or rolled ear 25, the purpose of which will be hereinafter described.

The device functions in the following manner:

The powder compact 16 together with its carrier is placed within the vanity case 11, after which the metallic band 19 is sprung into position with its upper edge in engagement with the inwardly-disposed shoulder 15. With the band in this position, it is apparent that the spring tongues 22 will engage the angular edge 18 of the compact carrier 17 and retain the same in position. When it is desired to renew the compact it is only necessary to remove the band 19 by grasping the lugs 25 between the thumb and fore finger, when the compact carrier is free to be moved outwardly of the vanity case in order that a new compact may be placed therein.

From the foregoing it is apparent that the present invention provides a new and improved means for securing powder compacts in vanity cases, and, furthermore, the invention provides such a means which is capable of permitting removal of the useless compact carrier in order that the new compact may be substituted therefor.

I claim:

1. A compact retainer for vanity cases comprising a resilient metallic band adapted for engagement with the side walls of a vanity case, and resilient tongues formed in said band and adapted to engage a compact to retain the same within the vanity case.

2. In a device of the character described, a vanity case having an inwardly-disposed annular shoulder, a powder compact adapted to be received within the vanity case, and a metallic band for securing the compact within the vanity case, said metallic band having its upper edge adapted to engage beneath the inwardly-disposed shoulder and its lower edge provided with a plurality of

resilient tongues adapted to engage the compact to retain the same within the vanity case.

3. A vanity case formed with an inwardly-disposed annular shoulder adjacent thereto, a compact carrier adapted to be received within the vanity case, a resilient band adapted to engage beneath the inwardly-dis-

posed annular shoulder of the vanity case and in engagement with the side walls thereof, and resilient tongues adapted to project inwardly of the vanity case from said resilient metallic band and into engagement with the compact to retain the same within the vanity case. 10

WILLIAM G. KENDALL.
